ANTENNA SYSTEM

Kurt Koschmieder, Falkensee, East-Havelland, Germany, assignor to C. Lorenz Aktiengesellschaft, Berlin-Tempelhof, Lorenzweg, Germany, a company

Application March 14, 1939, Serial No. 261,707
In Germany April 2, 1938

2 Claims. (Cl. 250—33)

This invention relates to antenna systems, and more particularly to improvements in that type of systems which is intended to exclusively respond to vertically polarized waves.

It is well known for the purpose of eliminating direction finding errors caused by the night or twilight effect to design antenna systems from the viewpoint that merely the vertically polarized but not the horizontally polarized waves shall be picked up by the antenna system. Antenna systems involving the aforesaid properties consist of a plurality of individual vertical antennae combined to suitable systems by means of horizontal conductor lines. These vertical antennae may either be dipoles, the so-called H-Adcocks, or half dipoles, the so-called U-Adcocks, which cooperate with earth or with a counterpoise.

This invention has for its object to provide means in order to improve the properties of the last mentioned type of antenna systems, that is, the U-Adcock antenna.

In antenna systems of the above mentioned type, only the vertical antennae become effective, while the energization of the horizontal interconnecting conductor lines is either avoided or even nullified. Two types of interconnecting lines are generally employed for this purpose, namely either single conductor lines or two-wire conductor lines. The single conductor lines may be provided with shieldings in order to prevent undesired energization thereof and to protect such lines against extraneous effects of radiation, while the currents flowing in the individual conductors of a two-wire line are rendered equal in magnitude but opposite in phase to so neutralize each other.

My invention consists in certain features of novelty which will be readily understood from the following description and be pointed out in the appended claims, reference being had to the accompanying drawings, in which

Figs. 1 and 2 schematically show two antenna arrangements of conventional type, Fig. 3 schematically shows one embodiment according to my invention, while Fig. 4 is a modification over the arrangement shown in Fig. 3.

The Fig. 1 shows a known U-Adcock antenna array comprising the vertical antennae V₁ and V₂ which are combined to an antenna system by means of the shielded horizontal single conductor lines H₁ and H₂ and the intermediate goniometer field coil F. Each of the horizontal lines H₁ and H₂ is provided with a grounded shielding member S₁ and S₂, respectively, as protection against undesired extraneous influ-

ences. The ground connections of these shieldings are indicated at E₁, E₂ and E₃. In order to impart directional effects to the antenna systems, a second similar antenna system (not shown) is arranged at right angles to the first mentioned system. Nevertheless, experience teaches that the above mentioned precautions are insufficient to avoid directional finding errors due to the fact that it has not been possible to reliably suppress the horizontal polarization. Careful investigations have proven that a capacitive coupling is set up between the vertical antennae V₁ and V₂ and the appertaining line H₁ and H₂, respectively, which coupling causes the aforementioned horizontal polarization. Such capacitive couplings are indicated in Fig. 1 as virtual condensers C₁ and C₂ for illustration.

Attempts have been made in order to eliminate this capacitive coupling phenomenon, by submerging the interconnecting horizontal lines in the earth, in contradiction to the lines H₁ and H₂ in Fig. 1 which are placed above the earth's surface. However, even in this case considerable horizontal components have been observed since in the first instance horizontally polarized waves still influence the submerged and shielded lines, and on the other hand waves reflected from the earth's surface affect the antennae V₁ and V₂ subsequent to a polarization change imparted to these waves.

My invention has for its object to reliably eliminate the heretofore mentioned difficulties. This is realized according to the main feature thereof by spacing each vertical antenna apart from the earth's surface at a given distance and by the provision of shielding means even for the vertical conductors which serve for connecting the horizontal conductor lines with the lower end of the antenna in its elevated position.

The Figs. 3 and 4 show two different ways for carrying out my invention. These two embodiments involve the only difference that the horizontal interconnecting lines H₁ and H₂ and their shieldings S₁ and S₂ are arranged at a certain space above the ground as illustrated in Fig. 3, while being submerged in the earth as shown in Fig. 4. The vertical antennae V₁ and V₂ are positioned at a given distance above the earth's surface and vertical portions L₁ and L₂ of the interconnecting lines are connected to the lower end of these antennae. Each vertical line portion L₁ and L₂ is provided with a shielding A₁ and A₂, respectively. These shieldings principally correspond to those of the horizontal in-

interconnecting lines and may be directly connected therewith. It is of course possible to employ suitably shielded cable lengths between the lower end of each antenna and the goniometer coil F. The length h of each of the vertical shieldings A₁ and A₂ between the lower end of each antenna and the earth's surface may be equal to the half or to the whole distance between the antennae V₁ and V₂.

10 The above described arrangement according to my invention is capable of considerably reducing capacitive coupling effects between the horizontal lines and the vertical antennae. Moreover, the vertical antennae are rendered substantially immune against waves being reflected from the earth's surface.

15 The means as disclosed in the foregoing merely by the way of few examples in connection with shielded single-wire lines are likewise applicable to antenna systems employing two-conductor lines for interconnecting the various vertical antennae. Moreover, my invention is applicable to transmitting as well as to receiving antenna systems.

What is claimed is:

1. An antenna system comprising a plurality of vertical antennae spaced apart from one another and having their lower end spaced at a distance from the earth's surface, horizontal conductor lines for interconnecting the said vertical antennae to form a directional antenna system, shields for said horizontal conductor lines, vertical conductor lines for connecting each vertical antenna with its appropriate horizontal conductor line, and a shielding for each of said vertical conductor lines extending between the lower end of each vertical antenna and the appropriate end of the shields provided about said horizontal conductor lines. 5 10

2. The invention according to claim 1, characterized in that the length of said shielding for each of said vertical conductor lines is substantially between the limits corresponding to one half to one full distance between two vertical antennae of said antenna system. 15 20
